UNITED STATES PATENT OFFICE.

JOSEPH W. FOLEY, OF OTTAWA, ONTARIO, CANADA.

RAZOR ATTACHMENT.

1,108,839.

Specification of Letters Patent. Patented Aug. 25, 1914.

Application filed November 29, 1912. Serial No. 734,184.

To all whom it may concern:

Be it known that I, JOSEPH W. FOLEY, a citizen of the United States, residing at Ottawa, in the Province of Ontario and Dominion of Canada, have invented new and useful Improvements in Razor Attachments, of which the following is a specification.

The present invention relates to razor attachments.

10 The device is intended to provide a simple, cheap and effective structure, which may be readily attached to a razor, and which will sustain the same at a proper inclination or angle to guide the cutting edge thereof 15 to its work.

With the above recited objects in view, the invention resides in the novel construction, combination and arrangement of parts hereinafter fully described and claimed.

20 In the drawing, Figure 1 is a perspective view of a razor provided with my improvement. Fig. 2 is a transverse sectional view through the same.

With the employment of the ordinary 25 razors, in the process of shaving, no means have been provided, whereby the cutting edge of the razor is at all times sustained at a proper inclination with regard to the surface over which it is worked. As a result 30 it has been found a severe task for an ordinary person to do his own shaving, and as a consequence he is forced to frequent tonsorial parlors which is objectionable to certain persons for various reasons. In the first 35 place if the parlor is occupied, and others are in waiting, a great loss of time is occasioned by the last person entering the shop. Again, the barbers do not supply individual razors for their patronage, and skin 40 rashes have thus not infrequently been caused. In the majority of cases, the individual prefers being his own barber, and as the safety razors are also open to objections, I have provided a simple, but effective guide which 45 may be readily secured to or detached from any ordinary razor blade.

In the accompanying drawing, the numeral 1 designates an ordinary razor blade to which is attached my improved guide 2. 50 The guide is preferably constructed from a

single piece of resilient material, and embodies a substantially rounded top 3 having inwardly curved side arms 4 which terminate a suitable distance away from the top. The lower longitudinal edges of the member are extended upwardly to provide normally contacting flat plates or members 5. These plates terminate a suitable distance away from the head of the device, and the upper edges of the said members are preferably flared away from each other as designated by the numeral 6.

With a construction as above described, it will be noted that a razor blade may be readily inserted between the plates and its upper edge engaged with the under face of the top of the device. The rounded inclined sides provide an effective guide whereby the razor may be sustained at an angle so as to properly direct its cutting edge to its work.

Having thus described the invention, what I claim is:—

A razor attachment comprising, in combination with a razor blade having a continuous flat edge and transversely concave sides merging into the edges of said flat edge, a resilient member fitting the blade and consisting of a single length of material bent upon itself to provide relatively springy 75 face engaging members co-extensive with the length of the blade, and a flat crown overlying and engaging the flat edge, concaved impinging members extending upwardly from the lower edges of the face engaging members co-extensive in length 80 therewith, the said impinging members fitting into the concavities in the sides of the blade for the major portion of the width of the blade, and each having its lower edge 85 gradually merging into the lower edge of the adjacent face engaging member whereby to provide a relatively broad lower edge 90 to engage against the face of the operator.

In testimony whereof I affix my signature in presence of two witnesses.

JOSEPH W. FOLEY.
